(57) **CLAIM**

I claim the ornamental design for an ear wax curette, as shown and described.

DESCRIPTION

FIG. 1 is a perspective view of an embodiment of an ear wax curette showing my new design;

FIG. 2 is a left side view thereof;

FIG. 3 is a right side view thereof;

FIG. 4 is a top view thereof;

FIG. 5 is a bottom view thereof;

FIG. 6 is an end view thereof;

FIG. 7 is an end view thereof, opposite that shown in FIG. 6;

FIG. 8 is a perspective view of a second embodiment of an ear wax curette showing my new design;

FIG. 9 is a left side view thereof;

FIG. 10 is a right side view thereof;

FIG. 11 is a top view thereof;

FIG. 12 is a bottom view thereof;

FIG. 13 is an end view thereof; and,

FIG. 14 is an end view thereof, opposite that shown in FIG. 13.
